VIBRATION-TRANSMISSION MECHANISM

Application filed November 11, 1926. Serial No. 147,658.

This invention relates to improvements in vibration transmission mechanisms, and has particular reference to an electrically modulated device for converting electrical impulses into audible sounds, the device being especially applicable for use with loud speakers, telephone receivers and like instruments.

An object of the invention is to provide a mechanism of practical, reliable and sturdy construction, which will effectively convert the electrical modulations into mechanical vibrations of maximum strength.

In accordance with the above object the armature of an electromagnetic device is so positioned with respect to its modulation coil that the vibration transmission element, utilized to transmit the vibrations of said armature to a diaphragm, may be connected directly to said armature.

A further object is to so mount the transmission element that the same may be used as the sole support for a vibratory diaphragm without placing undue stress, occasioned by the weight of said diaphragm, upon the point of connection of said element with its armature.

The above and other objects will appear more clearly from the following detailed description, when taken in connection with the accompanying drawing, which illustrates a preferred embodiment of the inventive idea.

In the drawing—

Figure 1 is a side elevation of the mechanism with its casing shown in section;

Figure 2 is a vertical longitudinal section through the mechanism taken on the line 2—2 of Figure 3;

Figure 3 is a front elevation of the mechanism with the casing shown in section;

Figure 4 is a top plan view; and

Figure 5 is an end elevation showing details of the armature mounting.

Referring more particularly to the drawing the transmission mechanism is shown as consisting of a casing 6 made of any desirable

material and which is rectangular or circular, as desired. One end of the casing is open and has mounted therein a disk or a plate 7, which is preferably of wood, and which is utilized as a means for attaching the unit to a standard or other support, said disk being of wood in order to absorb and more readily prevent the transmission of vibrations to the standard upon which the unit is mounted.

Suitably secured to the inner face of the disk 7 is a mounting plate 8, which is preferably a casting, and which is provided at one end with a boss 9. Interposed between the mounting plate 8 and the ends of the magnet 10 are the opposed pole pieces 11, said magnet and pole pieces being secured together by the supporting bar 12 bridging the ends of the magnet 10 and having screws 13 extending therethrough and into the pole pieces. The inner spaced ends of the pole pieces 11 have mounted therebetween the modulation coil 14, the extremities of which are connected by wires 15 to the contacts 16 secured to the insulating plate 17 which is attached to the mounting plate 8 and provided with terminal posts 18 for connection to a suitable circuit. The modulation coil 14 is in the form of a spool having a central opening 19 therein through which the free end of the armature 20 extends. Adjustably secured to the pole pieces 11 on one side of the coil 14 are auxiliary positive and negative pole pieces 21 and 22, respectively, while arranged on the opposite side of said coil 14 and also secured to the pole pieces 11 are the positive and negative auxiliary pole pieces 23 and 24, said pole pieces having the ability, when the coil 14 is energized, to flex the armature 20 in order to impart a vibratory movement to the transmission rod 25, the inner end of which is secured directly to the armature 20 between the coil 14 and the point of suspension of the armature on the plate 8. Thus when the armature 20 is flexed by

the energization of the coil 14 the vibrations of the armature will be transmitted directly to the rod 25 and from thence to the diaphragm 26 partially illustrated in Figure 2 and being of any desirable type. The entire weight of this diaphragm is carried by the rod 25 and this is made possible by the provision of a supporting means for said rod 25 which will relieve any strain occasioned by the weight of the diaphragm upon the point of connection of the inner end of the rod with the armature 20. This supporting means is in the form of a flexible element 27 having one end secured to the supporting bar 12 and its other end attached to the rod 25 intermediate its ends. The element 27 is made flexible in order that the same will not hinder the free vibration of the rod 25, but at the same time it supports said rod sufficiently to permit of the diaphragm being mounted upon its outer extremity and prevent any undue lateral movement of the rod which may be otherwise occasioned by the flexing of the armature 20 so that the vibrations of the rod will, for all practical purposes, be in directions longitudinally thereof.

With the free end of the armature 20 extending through the coil 14 and the rod 25 connected to an intermediate part of the armature, the other extremity of the latter is secured to the mounting plate in such manner that the first named extremity may be mechanically and magnetically balanced between the pole pieces and maintained in such position. For this purpose the boss 9 is provided with the projections 28 arranged in transverse alignment with respect to the armature 20 and upon which the fixed end of said armature rests. On the opposite side of the armature from that engaged by the projection 28 and directly opposed to the latter, said armature also has engaged therewith the plate 29 which is in turn contacted by an arcuate leaf spring 30. A screw or other adjusting device 31 is extended through the spring plate, armature and into the boss 9 so that by turning the screw 31 a greater or lesser degree of pressure may be exerted upon the armature. In order to adjust the armature a set screw 32 is extended through the disk 7 in screw threaded relation with the boss 9 with the inner end of the screw contacting the fixed extremity of the armature 20 so that by turning the screw and also utilizing the screw 31, if necessary, a slight adjustment of the free end of the armature may be had.

What is claimed is:

60 In a vibration transmission mechanism, a flexible vibratory armature, an electromagnetic device, means at one end of said armature to magnetically and mechanically balance the other end thereof in the magnetic field of said device, a vibration transmission

rod directly connected to the armature at a point between said balancing means and said electromagnetic device, a magnet associated with said electromagnetic device, a supporting bar bridging the ends of said magnet, 70 and a flexible element secured at one end to said supporting bar and at its other end to an intermediate portion of said rod to support the latter.

In testimony whereof I have affixed my signature.

VITALIS HIMMER.
